Primary Examiner — Keith J Wilson(74) *Attorney, Agent, or Firm* — Suiter Swantz pc llo(57) **CLAIM**

The ornamental design for a sprinkler, as shown and described.

DESCRIPTION

FIG. 1 is a perspective view showing our new design;

FIG. 2 is a left side view thereof;

FIG. 3 is a right side view thereof;

FIG. 4 is a rear elevation view thereof;

FIG. 5 is a front elevation view thereof;

FIG. 6 is a top plan view thereof; and,

FIG. 7 is a bottom plan elevation view thereof.

The broken lines showing anchor straps, seams, a top handle, and valves of FIGS. 1-7 form no part of the claimed design.

1 Claim, 7 Drawing Sheets(56)
